UNITED STATES PATENT OFFICE.

THOMAS B. FERGUSON, OF NEW YORK, N. Y.

LIQUID-FUEL BURNER.

1,111,449.

Specification of Letters Patent. Patented Sept. 22, 1914.

Application filed August 21, 1913. Serial No. 736,031.

To all whom it may concern:

Be it known that I, THOMAS B. FERGUSON, a citizen of the United States of America, and a resident of New York, in the borough 5 of Brooklyn, county of Kings, and State of New York, have invented certain new and useful Improvements in Liquid-Fuel Burners, of which the following is a specification.

This invention relates to burners for kerosene and other liquid hydrocarbons, and is particularly intended for producing a heating flame; the burner being therefore adapted for use in heaters of various types, stoves, furnaces, ranges etc.

15 My invention embodies modifications of and improvements in the burner for the same purpose illustrated and described in my application for U. S. Letters Patent filed January 5, 1912, Sr. No. 669,620. The burner of

20 said prior application is characterized by flame-guarding and flame-deflecting means arranged to deflect a flame jet backwardly or downwardly and outwardly in the form of an annulus; which flame then spreads laterally and outwardly, inclosing a space 25 through which passes a return bend heating tube, through which tube the oil is passed in order that same may be heated, and, preferably, vaporized before it is projected outward from the burner to form the flame.

30 The construction of such burner is such that the flame does not play directly upon the heating tube, except where such tube passes at right angles across the path of the flame; 35 and the portions of such tube so passing across the flame are so small, and are so situated with respect to the main heating portion of the tube, that such slight direct action of the flame has no detrimental effect.

40 The main portion of the heating tube is heated in the main by heat radiated from the flame but modified by a downdraft of air produced by the flame itself in its passage through the burner. The burner herein 45 illustrated and described is of the same general nature as the burner of my said prior application, but embodies certain modifications and improvements in structure, arrangement, etc.

50 The objects of my invention are to produce a relatively simple and inexpensive and very effective burner of the class described, which shall produce very perfect combustion, which may be heated up very quickly

and easily, and which is compact and substantial in construction. 55

I will now proceed to describe my invention with reference to the accompanying drawings, and will then point out the novel features in claims. 60

In said drawings: Figure 1 shows a central vertical section of one form of my improved burner, the section being taken on the line $x-x$ of Fig. 5. Fig. 2 shows another central vertical section of my improved burner, the section being taken on line $y-y$ of Fig. 5; i. e., being taken at right angles to the section of Fig. 1. Fig. 3 is a detail view illustrating an alternative construction of primary heating burner 70 which may be employed. Fig. 4 is a detail elevation and partial section of one end of the fuel heating tube. Fig. 5 is a top view of the burner. Fig. 6 shows a horizontal section of the burner on the line $z-z$ of Fig. 2; and Fig. 7 shows a horizontal section of the lower portion of the burner on the line $w-w$ of Fig. 2. Fig. 8 shows an outside elevation of the burner and the support therefor. Fig. 9 is a detail outside elevation 80 of the burner, looking from the left of Fig. 8. Fig. 10 is a sectional elevation of the burner base and associated parts, the section being taken on the line $v-v$ of Fig. 7. 75

In the drawings, numeral 5 designates a 85 burner base provided with an internally threaded aperture 4 adapted to receive a valved duct 2 leading from a pressure tank 1, (Fig. 8) which tank is adapted, as is customary in burners of this class, to supply oil 90 under pressure to the burner. The burner base is further provided with other apertures 6 and 7, screw threaded to receive gland-bushings 6' and 7' respectively, which gland bushings are mounted upon the ends 95 of a fuel heating tube 3 of inverted U-form. The aperture 6 connects with the aperture 4, and the aperture 7 connects with a conduit 8 provided in burner base 5, which conduit connects with a conduit 9, in the central portion of the burner base, a burner tip 10 being provided at the top of this conduit, which burner tip 10 is provided with a small burner orifice 11. A valve 12, provided in conduit 2, serves for the control of the flow 100 of oil to the fuel heating tube, and so regulates the flow of gas, or heated oil, or both, to the burner orifice 11. 105

The space 13 immediately above the burner orifice 11 constitutes an initial combustion space, this space being inclosed by a two-part shell, 14-15, member 14 of which rests upon the burner tip 10 and is provided with suitable air inlet openings 16. Member 15 rests upon the member 14 and is provided at its top with a suitable gas exit opening 17. Above the gas exit opening 17 there is a bell-shaped member 19 constituting a flame deflector, the sides of which extend down below the gas orifice 17 as shown particularly in Fig. 2, said deflector being supported from the platform 18 (formed integrally with member 14) by means of legs 20 with which such flame deflector 19 is provided. Within the flaine deflector 19, and supported by it, there is a secondary deflector, 27, likewise of approximate bell form, and the sides of which are spaced away from the inner surfaces of the deflector 19 somewhat. This secondary deflector 27 I commonly form of a material of high heat conductivity, such for example as copper, while the main deflector, 19, is commonly formed of cast iron, cast iron being stronger and more rigid than copper at the temperatures to which these parts are subjected.

The platform 18 is provided with a depending annular flange 21 and is also provided, within such flange, with flame orifices 22 and flame nozzles 23, the latter extending downward in close proximity to the air inlet openings 16 of the burner member 14. Outside of the depending flange 21, the platform 18 is provided with other flame orifices 24; and above, and resting upon the platform 18, is another perforate platform 25 having in it orifices 26 and likewise provided with an upwardly projecting flange 28, surrounding, but spaced somewhat away from, the lower portion of the flame deflector 19. The platform 18 is further provided with an outer depending flange 29, provided with a bottom plate 30 itself provided with an annular opening 31 through which much of the air for the support of combustion of the burner passes; the said flange 29 and bottom plate 30 in closing a relatively quiet mixing and air combining space 32 in which air passing up through opening 31 mixes with the flame, as hereinafter described.

For the initial heating of the burner I provide supplemental heating burners, 33, carried by the burner base 5 and comprising burner tubes 34 provided with air inlet ports 35, the flow of air into which may be controlled by perforate rotatable collars 36. Within the lower portions of each of these burner tubes 34 there is a body of porous absorbent material 37 such as cotton, wool, or asbestos, surrounded by a gauze cylinder 37a. These burner tubes 34 may be provided with air inlet tubes 38,

open at the bottom and at the top and sides as shown, or, as indicated in Fig. 3, these tubes, there designated by numeral 38a, may be closed at the bottom and may contain wicking 39.

At their upper ends, the burner tubes 34 are provided with removable burner tips 40. Resting upon these tips there is a perforate shield 41, inside which is a deflector 42 provided with orifices 43 close to the 75 sides of the burner member 14.

Oil is supplied to the absorbent material of heater burners 33 by means of tubes 44 customarily connected to a coupling 45 (Figs. 2 and 7) supported by the burner base 5; to which coupling oil is supplied by a pipe 46. Any suitable means may be employed for the regulation of the supply of oil through this pipe 46; I prefer some automatic level-maintaining oil-feed device, such as is commonly used, for example, in the well known "Student" lamp, but do not limit myself to any particular device for this purpose, and therefore have not shown, in the drawings, any particular device for this purpose.

For cleaning the burner orifice 11 I provide a screw cleaning rod 50, located within the duct 9, and guided at its upper end by a perforate collar 51. This cleaning rod 50 has a needle point at its upper end, which may be passed through the burner orifice 11 by screwing up said rod. Such needle point also forms, with the orifice 11, a needle valve for further regulation of the 100 supply of gas or heated oil.

The operation of the burner is as follows: To start the burner in operation it is first necessary to heat the burner, particularly the part 15 and 27; to which end the heating burners 33, previously mentioned, are provided. These heating burners 33 may be lighted by means of a lighted match or taper, applied to the absorbent material 37 through the orifices 35; the rings 36 being lifted, if necessary, to permit the insertion of such lighted match or taper. The flames from these heating burners, emerging through the burner tips 40, are deflected inward by the deflector 42 and pass up along the member 14 of the burner and through the orifices 16 of the burner, heating quickly and to a high degree the members 15 and 27. When these parts are sufficiently heated, (which usually takes only a few minutes), the oil for the main burner is turned on by the opening of the valve 12 and thereby a jet of oil or oil vapor is caused to issue from the burner orifice 11, mingling with air in the space 13 and igniting automatically by contact with the hot deflector 27; the flame so produced heating to a still higher degree the members 15 and 27 so that almost instantly the flame becomes a blue flame. When the 130

burner is in full operation combustion initiates within the space 13 but is not complete in such space, the burning gases issuing from the orifice 17 and being deflected downward by the deflectors 27 and 19. I find that much of the flame passes through the orifices 22 in platform 18 and through the flame nozzles 23 in that platform, and passes underneath the flange 21 of that platform and then up through the orifices 24 of that platform and through the orifices 26 of the upper platform, 25, while other portions of the burning gases pass between the platforms 18 and 25 and up through the orifices 26, the flame burning, above the platform 25, as a flame annulus surrounding the fuel heating tube 3 but without impinging upon such tube, except at the points where the sides of such tube 3 pass at nearly right angles through the nearly horizontal portions of the currents of the burning gases. The oil within the fuel heating tube 3 is heated by heat radiated from this flame annulus, as is necessary for best combustion 25 of kerosene and heavier oils in burners of this type. The heat produced is very intense, and owing to the great spread given to the flame, the burner is capable of developing a great amount of heat, while the combustion is very perfect. Combustion is facilitated, and the heating of the fuel heating tube modified, by a downward draft of air within the flame annulus passing through the space between the flange 28 35 of the platform 25 and the deflector 19.

The foraminous guard 41 serves mainly for the protection of the flame of the initial heating burners 33, from air drafts, but does not interfere with combustion of the main flame, which combustion goes on to a considerable extent within the mixing chamber 32. I find also that some portion of the burning gases of the main flame, passing downward through the flame nozzles 23, 45 pass into the air inlet openings 16 and up through the initial combustion chamber 13; such passage of a portion of the flaming gases of the main flame back into the initial combustion chamber, being due, doubtless, to eddy currents induced by the air flowing in through these air openings 16. The heat of the portion of the flaming gases so passing through the air inlet openings 16 aids materially in effecting primary combustion 50 within this chamber 13, such as seems to be essential for perfect combustion of kerosene and heavier oils.

As pointed out in my said prior application, the supply of a small amount of water to the flame of these burners seems to aid materially in the combustion, producing a more intense flame; and for this purpose I provide a pipe 52. Water drops down into a trough 52' (Fig. 10) formed in base 5.

65 The perforate collar 51 besides guiding

the needle valve and cleaning rod 50 performs the important function of providing a material restriction in the conduit 9, well below the burner orifice 11. As a result of this restriction, even though the portion of conduit 9 below collar 51 be filled with heated liquid fuel, the space 53 between collar 51 and burner orifice 11, will, in practice, be filled with gas or vapor; for the restriction offered by the perforations 54 of collar 51 is sufficient to permit the heated oil to flash into vapor or gas after its passage through such perforations. The space 53 therefore constitutes a vaporizing chamber.

In Figs. 1 and 4 I have indicated means 80 for the gas tight connection of the ends of the fuel heating tube to the burner base which I have found particularly efficient. It is rather difficult to make a tight joint between the burner base and the fuel heating 85 tube by ordinary means, for, the oil in the fuel heating tube being highly heated and therefore very fluid, and moreover being under considerable pressure, is apt to ooze out through any ordinary joint. To prevent 90 such oozing out of the oil I provide, near each end of the vaporizing tube a collar 55, screw threaded upon the corresponding end of the vaporizing tube, the screw threads being very tight fitting. Beneath this collar I provide, in the corresponding recess of the burner base, fibrous packing material 56, such as cotton, wool, or a mixture of cotton or wool fibers with rubber. Asbestos may also be used. The gland bushings 6' and 7' 100 force these collars 55 down, so compressing the packing material tightly against the shoulders formed at the bases of the recesses 6 and 7 in the burner base. Heretofore in burners of this type, mere gland 105 bushings such as 6' and 7' have been provided, to compress any packing material which may be used, and, since the gland bushings must rotate freely upon the vaporizing tube, I have found that some oils tend to seep out between the vaporizing tube and gland bushing, and this seepage I have found is prevented by the collars 55 which are screw threaded so tightly upon the end of the tube 3 that no leakage of the oil can 110 take place through the threads.

What I claim is:—

1. A burner comprising in combination fuel - jet - projecting means, a deflector arranged to deflect the said jet rearwardly and as an annulus, a platform beneath such deflector, and a mixing and air inlet chamber beneath such platform and having an air inlet, said platform having openings through which such annular flame stream will pass into the mixing and air inlet chamber and other openings through which such flame annulus will pass outwardly from the mixing chamber.

2. A burner comprising in combination

fuel - jet - projecting means, a deflector arranged to deflect the said jet rearwardly and as an annulus, a platform beneath such deflector, and a mixing and air inlet chamber beneath such platform and having an air inlet, said platform having openings through which such annular flame stream will pass into the mixing chamber and other openings through which such flame annulus will pass outwardly from the mixing chamber, and a baffle separating the openings through which such annulus will pass into the mixing and air inlet chamber from the openings through which such flame annulus will pass from the mixing chamber.

3. A burner comprising in combination fuel - jet - projecting means, an initial combustion chamber inclosing the space immediately beyond such jet-projecting means, such initial combustion chamber having an air inlet opening and a flame outlet opening, a platform extending laterally from said initial combustion chamber and located beneath said flame outlet opening, a flame deflector beyond the flame outlet of said initial combustion chamber and arranged to deflect the flame from such outlet rearwardly as a flame annulus, a mixing and air inlet chamber beneath said platform, said platform having openings through which such flame annulus will pass into said mixing and air inlet chamber, and having other openings through which the flame annulus will pass from such mixing and air inlet chamber.

4. A burner comprising in combination fuel-jet-projecting means, an initial combustion chamber inclosing the space immediately beyond such jet-projecting means, such initial combustion chamber having an air inlet opening and a flame outlet opening, a platform extending laterally from said initial combustion chamber and located beneath said flame outlet opening, a flame deflector beyond the flame outlet of said initial combustion chamber and arranged to deflect the flame from such outlet rearwardly as a flame annulus, a mixing and air inlet chamber beneath said platform, said platform having openings through which such flame annulus will pass into said mixing and air inlet chamber, and having other openings through which the flame annulus will pass from such mixing and air inlet chamber, and a baffle between the openings through which flame will pass into the mixing chamber, and the openings through which the flame will pass from said mixing and air inlet chamber.

5. A burner comprising in combination fuel-jet-projecting means, an initial combustion chamber inclosing the space immediately beyond such jet-projecting means, such initial combustion chamber having an air inlet opening and a flame outlet opening, a platform extending laterally from said

initial combustion chamber and located beneath said flame outlet opening, a flame deflector beyond the flame outlet of said initial combustion chamber and arranged to deflect the flame from such outlet rearwardly as a flame annulus, a mixing and air inlet chamber beneath said platform, said platform having openings through which such flame annulus will pass into said mixing and air inlet chamber, and having other openings through which the flame annulus will pass from such mixing and air inlet chamber, and a second platform above and spaced away from said first platform and separated therefrom, and provided with openings through which flame gases passing between the two platforms may escape.

6. A burner comprising in combination fuel-jet-projecting means, an initial combustion chamber inclosing the space immediately beyond such jet-projecting means, such initial combustion chamber having an air inlet opening and a flame outlet opening, a platform extending laterally from said initial combustion chamber and located beneath said flame outlet opening, a flame deflector beyond the flame outlet of said initial combustion chamber and arranged to deflect the flame from such outlet rearwardly as a flame annulus, a mixing and air inlet chamber beneath said platform, said platform having openings through which such flame annulus will pass into said mixing and air inlet chamber, and having other openings through which the flame annulus will pass from such mixing and air inlet chamber, and a second platform above and spaced away from said first platform and separated therefrom, and provided with openings through which flame gases passing between the two platforms may escape, said second platform having an opening, for the passage of air into the space between said two platforms.

7. A burner comprising in combination fuel-jet-projecting means, an initial combustion chamber surrounding the space beyond said jet projecting means and having an air inlet and a flame outlet, a deflector located in the path of the flame escaping from such flame outlet, such deflector arranged to deflect the flame backwardly as a flame annulus, a platform extending laterally from said initial combustion chamber, and a mixing and air inlet chamber beneath said platform provided with an air inlet, said platform having openings for the passage of such flame annulus into the mixing and air inlet chamber, and other openings for the passage of such flame annulus from the mixing and air inlet chamber, said platform further provided with a downwardly extending baffle flange between the openings through which flame may enter

said mixing and air inlet chamber and the opening through which flame may escape from said mixing and air inlet chamber.

8. A burner comprising in combination 5 fuel-jet-projecting means, an initial combustion chamber inclosing the space beyond such projecting means and having an air inlet and a flame outlet, a deflector located beyond such outlet and arranged to deflect 10 the flame rearwardly as a flame annulus, a platform extending laterally from said initial combustion chamber and provided with a downwardly extending flange and with a bottom plate, such platform, flange and bottom plate together inclosing a mixing and air inlet chamber, there being an opening for the entrance of air to said mixing and air inlet chamber, said platform being perforate.
- 15 9. A burner comprising in combination fuel-jet-projecting means, an initial combustion chamber inclosing the space beyond such jet and provided with an air inlet opening and a flame outlet, a deflector beyond such flame outlet arranged to deflect 20 the flame rearwardly as a flame annulus, and a platform extending laterally from said initial combustion chamber and provided with downwardly projecting nozzles.
- 25 10. A burner comprising in combination fuel-jet-projecting means, an initial combustion chamber inclosing the space beyond such jet and provided with an air inlet opening and a flame outlet, a deflector beyond such flame outlet arranged to deflect 30 the flame rearwardly as a flame annulus, and a platform extending laterally from said initial combustion chamber and provided with downwardly projecting nozzles,
- 35 40 the lower orifices of said nozzles located in proximity to the air inlet of said initial combustion chamber.

11. A burner comprising in combination fuel-jet-projecting means and a deflector located in the path of the jet therefrom and arranged to deflect the flame of such jet rearwardly and outwardly as a flame annulus, such deflector comprising a deflecting body of material of high heat conductivity 45 and an annular support therefor located outside of such deflecting body and in the main spaced well away therefrom.

12. A burner comprising in combination a burner base, provided with fuel-jet-projecting means and with an initial heating burner, a deflector in the path of the jet from such projecting means, and another deflector arranged to direct the flame of such initial heating burner toward said 55 first-mentioned deflector.

13. A burner comprising in combination fuel-jet-projecting means, an initial combustion chamber surrounding the space immediately beyond said projecting means and 60 provided with an air inlet and a flame out-

let, an initial heating burner and a deflector arranged to direct the flame of such initial heating burner toward the air inlet of said initial combustion chamber.

14. A burner comprising in combination 70 fuel-jet-projecting means, an initial combustion chamber surrounding the space immediately beyond such projecting means and provided with an air inlet and a flame outlet, a deflector beyond the flame outlets of 75 said initial combustion chamber, an initial heating burner, and another deflector arranged to deflect the flame of such initial heating burner toward the air inlet of said initial combustion chamber.

15. A burner comprising in combination 80 a burner base provided with fuel-jet-projecting means, an initial combustion chamber surrounding the space immediately beyond such projecting means and provided with an air inlet and a flame outlet, said burner base provided further with an initial heating burner located in proximity to said fuel-jet-projecting means, and a deflector arranged to direct the flame of such initial heating burner toward the air inlet of said initial combustion chamber.

16. A burner comprising in combination 85 a burner base provided with fuel-jet-projecting means, an initial combustion chamber 90 surrounding the space immediately beyond said projecting means and provided with an air inlet and a flame outlet, a plurality of initial heating burners carried by said base and arranged about the fuel-jet-projecting 95 means, and a deflector arranged to direct the flames of such initial heating burners toward the initial combustion chamber.

17. A burner comprising in combination 100 a burner base provided with fuel-jet-projecting means, an initial combustion chamber surrounding the space immediately beyond such projecting means and provided with an air inlet and a flame outlet, a flame deflector in the path of gases passing 105 through the flame outlet of said combustion chamber, a plurality of initial heating burners carried by said base and arranged about said fuel-jet-projecting means, and means for deflecting the flames of said initial heating burners into the air inlet of said initial combustion chamber, whereby the flames of said initial heating burners are caused to heat both said chamber and the flame deflector beyond such chamber.

18. A burner comprising in combination 110 fuel-jet-projecting means, an initial combustion chamber surrounding the space immediately beyond such projecting means, and provided with an air inlet and a flame outlet, an initial heating burner, means for deflecting the flame of such initial heating burner toward said initial combustion chamber, and a flame guard for protecting the 115 flame of said initial heating burner.

19. A burner comprising in combination fuel-jet-projecting means, an initial combustion chamber surrounding the space immediately beyond said projecting means and provided with an air inlet and a flame outlet, a plurality of initial heating burners arranged about said fuel-jet-projecting means, deflecting means arranged to deflect the flames of such initial heating burners toward such initial combustion chamber, and a foraminous guard surrounding said deflecting means and arranged to protect the flames of said initial heating burners.
20. A burner comprising in combination fuel-jet-projecting means, an initial combustion chamber surrounding the space immediately beyond such projecting means and provided with an air inlet and a flame outlet, a flame deflector located beyond said flame outlet and arranged to deflect the flame from said outlet backwardly and as a flame annulus, and means for carrying a portion of such flame into proximity to the said air inlet of said initial combustion chamber.
21. A burner comprising in combination a burner base provided with a centrally-arranged fuel-jet-projecting means and with passages at the sides thereof for connection of a vaporizing tube to said burner base, and a vaporizing tube connected to said passages, one of said passages further provided with a fuel connection and the other of said

passages connected to said fuel-jet-projecting means, and a plurality of initial heating burners likewise carried by said burner base and arranged about the fuel-jet-projecting means and substantially parallel thereto.

22. A heating burner comprising in combination a tube closed at the bottom and open at the top and provided intermediate said closed bottom and open top, with a lateral air inlet, absorbent material within said tube, means for the supply of liquid fuel to such absorbent material, and a burner tip resting removably upon said tube and provided with a flame orifice.

23. A heating burner comprising in combination a tube closed at the bottom and open at the top and provided intermediate said closed bottom and open top, with a lateral air inlet, absorbent material within said tube, means for the supply of liquid fuel to such absorbent material, and another tube within said first mentioned tube and provided with lateral orifices above said absorbent material.

In testimony whereof I have signed this specification in the presence of two subscribing witnesses.

THOMAS B. FERGUSON.
